(57) **CLAIM**

The ornamental design for a multi-purpose building as shown and described.

DESCRIPTION

FIG. 1 is a front perspective of the multi-purpose building. FIG. 2 is a right side view of the building of FIG. 1. FIG. 3 is a left side view of the building of FIG. 1. FIG. 4 is a top view of the building of FIG. 1. FIG. 5 is a rear view of the building of FIG. 1; and, FIG. 6 is a duplicate view of the building of FIG. 1. The even-length broken lines depict portions of the multi-purpose building that form no part of the claimed design. The dash-dot broken lines depict the boundaries of the claimed design, and form no part thereof.
